FOLDING WALL PANEL

Wesley B. Dickson, Orange, Calif., assignor to Advanced Equipment Corporation, Anaheim, Calif., a corporation of Washington

Filed Dec. 21, 1964, Ser. No. 83,091

Term of patent 14 years

(Cl. D13—1)

FIG. 1 is an isometric view of a folding wall panel showing my new design;

FIG. 2 is a side elevation thereof;

FIG. 3 is a right end elevational view thereof;

FIG. 4 is a top plan view thereof;

FIG. 5 is an enlarged partial section taken along the line 5—5 of FIG. 1; and

FIG. 6 is an enlarged partial section taken along the line 6—6 of FIG. 1.

I claim:

The ornamental design for a folding wall panel, substantially as shown.
